(57) **CLAIM**

The ornamental design for a tailpiece for a stringed instrument, as shown and described.

DESCRIPTION

FIG. 1 is a top view of a tailpiece for a stringed instrument showing my new design;

FIG. 2 is a bottom view thereof;

FIG. 3 a left side view thereof;

FIG. 4 a right side view thereof;

FIG. 5 is a back side view thereof;

FIG. 6 a front side view thereof;

FIG. 7 is a first perspective view thereof;

FIG. 8 is a second perspective view thereof, showing the design as used with environmental subject matter;

FIG. 9 is a third perspective view thereof, showing the design as used with environmental subject matter; and,

FIG. 10 is a perspective view of a tailpiece for a stringed instrument showing another embodiment of my new design, as used with environmental subject matter.

In FIGS. 1-10, the broken lines on the tailpiece for a stringed instrument represent the portions of the design that form no part of the claim. In FIGS. 8-10, the broken lines showing portions of the stringed instrument illustrate the design as used with environmental subject matter and form no part of the claimed design.
